Attorney

UNITED STATES PATENT OFFICE.

GEORGE B. GWYNES, OF ANDERSONVILLE, GEORGIA.

PLOWBLADE.

Application filed December 12, 1921. Serial No. 521,790.

To all whom it may concern:

Be it known that I, GEORGE B. GWYNES, a citizen of the United States, residing at Andersonville, in the county of Sumter and 5 State of Georgia, have invented certain new and useful Improvements in Plowblades, of which the following is a specification, reference being had to the accompanying drawings.

10 This invention relates to certain improvements in plow blades, and it is an object of the invention to provide a device of this general character having novel and improved means whereby the same is reinforced or 15 strengthened in a manner whereby the life of the blade is materially prolonged.

Another object of the invention is to provide a novel and improved device of this general character consisting of a blade having 20 a portion reinforced or strengthened, said portion being extended forwardly to provide an entering nose and wherein a wing is provided at either or both sides of said reinforced or strengthened portion, said 25 wing being of a thickness less than the thickness of the reinforced or strengthened portion and of a thickness substantially equal to the thickness of the entering edge of the nose so that said blade and nose will 30 wear at substantially the same ratio so that the general formation of the plow is maintained.

An additional object of the invention is to provide a novel and improved device of 35 this general character provided with a forwardly directed nose or extension, the inward or rear portion of which is reduced in width to provide for clearance so that the desired travel of the blade within the soil is 40 materially facilitated and wherein the nose is preferably of a chisel type to facilitate its penetration within the soil.

The invention consists in the details of construction and in the combination and arrangement of the several parts of my improved plow blade whereby certain important advantages are attained and the device rendered simpler, less expensive and otherwise more convenient and advantageous 50 for use, as will be hereinafter more fully set forth.

The novel features of my invention will hereinafter be definitely claimed.

In order that my invention may be the 55 better understood, I will now proceed to de-

scribe the same with reference to the accompanying drawings, wherein:

Figure 1 is a view in perspective of a plow blade constructed in accordance with an embodiment of my invention and of a 60 subsoiler type;

Figure 2 is a sectional view taken substantially on the line 2—2 of Figure 1;

Figure 3 is a sectional view taken substantially on the line 3—3 of Figure 1; 65

Figure 4 is a perspective view of a shovel blade constructed in accordance with an embodiment of my invention; and

Figure 5 is a view in perspective of a turner blade constructed in accordance with 70 an embodiment of my invention.

As disclosed in Figures 1, 2 and 3 of the drawings, B denotes a blade constructed in accordance with an embodiment of my invention and which is rolled or otherwise 75 formed in a manner to provide a central and longitudinally extending rib or corrugation 1 concavo-convex in cross section with its convex face outwardly or upwardly directed. The rib or corrugation 1 has its upper or outer end continued by the stem 2 which is adapted to be secured to a plow stock in any ordinary or preferred manner. 80

The forward or lower end of the rib or corrugation 1 is extended to provide a nose 85 3, the free extremity of which is flattened, as at 4, and provided with a chisel edge 5. The nose 3 gradually decreases in width from its outer end to the blade proper and this is of material advantage in view of the fact that 90 it provides an effective clearance while the plow is in use.

The blade B is preferably rolled and during its production or formation, the wings 6 are formed, said wings extending outwardly 95 and laterally from the opposite sides of the rib or corrugation 1 and are of a thickness materially less than the thickness of the rib or corrugation 1. It is preferred that each of the wings 6 be of a thickness substantially 100 equal to the outer or flattened portion 4 of the nose 3. This is of especial advantage because the forward or working edges 7 of the wing 6 will wear backwardly at substantially the same ratio as the wear of the flattened portion 4 so that the life of the blade is materially prolonged. 105

It has also been found of especial advantage to have the chisel edge 5 of the flattened portion 4 arcuate in form with the bow ex- 110

tending outwardly. By this arrangement, it has been fully demonstrated in actual use that the entering nose 3 is prevented from wearing inwardly of its sides so that the nose 3 is at all times in the best possible condition for working.

By having the nose 3 reduced rearwardly in width, it has also been established in actual use that as said nose wears, no interference is had to its efficiency in entering or penetrating the soil.

In Figure 4, I disclose a blade B' of a shovel type and which is constructed in substantially the same manner as the blade 15 B hereinbefore referred to except as to the design and configuration of the blade 6'. The blade 6, as illustrated in Figures 1, 2 and 3, is of a type to particularly adapt the blade for use as a subsoiler.

20 In Figure 5, I illustrate an embodiment of my invention wherein the blade B'' is of a turner type and wherein a single wing 6'' is employed and wherein the rib or corrugation 1^a is positioned along a side marginal portion of the blade.

From the foregoing description it is thought to be obvious that a plow blade constructed in accordance with my invention is particularly well adapted for use by reason

of the convenience and facility with which it may be assembled and operated, and it will also be obvious that my invention is susceptible of some change and modification without departing from the principles and spirit thereof and for this reason I do not 30 wish to be understood as limiting myself to the precise arrangement and formation of the several parts herein shown in carrying out my invention in practice except as hereinafter claimed. 35

40 I claim:

As a new article of manufacture, a plow blade embodying a reinforcing rib of a thickness greater than the thickness of the remaining portion of the blade, said rib being extended to provide an entering nose, said nose decreasing in width from its outer end to the blade proper, the outer end portion of the nose being flattened, the outer margin of the nose being arcuate in form with the bow outwardly directed, said margin being provided with a chisel edge, the rib being concavo-convex in cross section with its 45 convex face upwardly directed.

50 In testimony whereof I hereunto affix my signature.

GEORGE B. GWYNES.
